BATHTUB

Robert Mueller, Decatur, Ill.

Original application December 23, 1935, Serial No. 55,910, now Patent No. 2,074,234, dated March 16, 1937. Divided and this application September 16, 1936, Serial No. 101,141.

7 Claims. (Cl. 4—173)

The present invention relates to bath tubs, particularly those of the apron type, and is a division of my copending application for bath tubs, Serial No. 55,910, filed December 23, 1935, now Patent No. 2,074,234, granted March 16, 1937.

An object of the invention is the formation of foot-receiving openings in the lower portion of the apron to permit the user to stand closer to the tub proper when either manipulating the faucets or bathing a child seated in the tub.

A further object is the provision of cover plates associated with the tub for closing the foot-receiving openings when the tub is not in use.

With the foregoing and other objects in view, the invention will now be more particularly described, reference being had to the drawing in which:

Figure 1 is a top plan view of a tub of the apron type illustrating one embodiment of the invention.

Figure 2 is a side elevation thereof.

Figure 3 is a vertical section taken on line 3—3 of Figure 1.

Figure 4 is an enlarged fragmentary view of one of the foot-receiving openings with the cover plate partly raised.

Figure 5 is a view showing a modified form of cover plate.

Figure 6 is an enlarged fragmentary view showing a pair of foot-receiving openings provided with interior wall elements forming blind pockets.

Figure 7 is a section taken on line 7—7 of Figure 6.

Referring to the drawing, and particularly to Figures 1 to 4, there is disclosed one form of the invention wherein numeral 10 designates the tub proper, which may be of any desired material, the form of tub herein shown being the usual metal enameled tub characterized by the usual side and end walls 11 and 12, respectively, and the outer apron 13.

It will be observed that the apron, as is usual in this type of tub, stands substantially vertical, and since there is an appreciable distance between the inner and outer walls of the tub, one leaning over and using the tub must necessarily stand back a considerable distance in a rather awkward position. To overcome this difficulty, I have formed a pair of spaced openings 14 in the lower portion of the apron, so that a person standing by the tub is enabled to stand closer, by reason of the toes of the feet projecting through the openings.

In this embodiment of the invention there are

provided cover plates 15 pivoted to the lower end of the apron to swing into and out of a position to entirely close the openings 14. Each cover plate is formed adjacent its lower extremity with an extension 16, and a suitable bolt or other fastening means 17 pivotally connects the cover plate to the apron. Preferably a knob or handle 18 projects outwardly from the face of the cover plate so that the latter may be easily grasped and moved from one position to the other.

In Figure 5 I have shown a further arrangement for closing the openings 14. In this connection I have provided sliding cover plates 19 of right angular formation. Each plate comprises a horizontal floor engaging flange 20 and a vertical apron engaging portion 21. By grasping the handle 22 each of these cover plates may be slid with respect to the lower portion of the apron to conceal or expose its respective opening 14. While no means have been disclosed, it is to be understood that either the flange 20 or the portion 21 may be positively connected to the floor or apron in such a manner as to permit the cover plate to slide with respect to the apron, but at the same time be anchored against accidental displacement.

With the present construction it will be apparent that anyone wishing to lean over the tub for the purpose of washing a child or cleaning the tub, may do so with greater ease than in the usual type of apron tub. By removing the cover plates from the openings 14, a person may pass the front portions of his feet through the openings and thus stand or sit closer to tub proper than would be possible without the provision of the openings. The provision of the cover plates adds to the appearance of the tub and when closed they prevent the accumulation of dust within the space enclosed by the apron.

In the embodiment shown in Figures 6 and 7, the cover plates 15 and 19 are not used. In this form, however, I prefer to secure to the inner face of the apron, pocket elements 23. These elements are adapted to entirely encompass the contour of the openings 14 and form therewith blind foot-receiving pockets. With this arrangement, any dust accumulating in these pockets may be easily swept out.

In Figures 1 and 3 there is disclosed an opening 24 in the flat horizontal portion of the tub between the apron and the side wall of the tub proper. This constitutes a hand hold and is adapted to be used in conjunction with the usual hand hold mounted in the wall of the room (not shown).

Such variations from the construction herein shown and described as are within the skill of a mechanic may, of course, be made without departing from the range of my invention.

5 I claim:

1. A bath tub having an apron, the lower portion of which is cut out to provide a foot receiving opening, and a cover plate for said opening movable into and out of operative position.
- 10 2. A bath tub having an apron, the lower portion of which is cut out to provide a foot receiving opening, and a cover plate for said opening pivotally connected to said apron.
- 15 3. A bath tub having an apron, the lower portion of which is cut out to provide a foot receiving opening, and a cover plate for said opening having a portion thereof adjacent its lower edge pivotally connected to the lower portion of the apron.
- 20 4. A bath tub having an apron, the lower portion of which is cut out to provide a foot receiv-

ing opening, and a cover plate for said opening slidably mounted with respect to the lower portion of the apron.

5 5. A bath tub having an apron, the lower portion of which is cut out to provide a foot receiving opening, and a cover plate for said opening of right angular formation having a horizontal floor engaging flange and a vertical apron engaging portion slidable with respect thereto.

10 6. A bath tub having an apron, the lower portion of which is provided with a pair of spaced foot receiving openings to anchor and prevent shifting of the feet.

15 7. A bath tub having an apron, the lower portion of which is provided with a pair of spaced foot receiving openings to anchor and prevent shifting of the feet, and means adjacent each of said openings to prevent entrance of foreign matter beneath the tub.
